(57) **CLAIM**

The ornamental design for a loading track, as shown and described.

DESCRIPTION

FIG. 1 is a front perspective view of loading track showing our new design;

FIG. 2 is a rear perspective view thereof;

FIG. 3 is a top plan view thereof;

FIG. 4 is a cross-sectional view taken along line 4-4 of FIG. 3;

FIG. 5 is a cross-sectional view taken along line 5-5 of FIG. 3;

FIG. 6 is a bottom plan view thereof;

FIG. 7 is a front elevational view thereof;

FIG. 8 is a rear elevational view thereof;

FIG. 9 is a right side elevational view thereof;

FIG. 10 is a left side elevational view thereof; and,

FIG. 11 is a front perspective view thereof shown within an environment of an assay processing system.

The broken line showing of the assay processing system in FIG. 11 depicts environmental structure and forms no part of the claimed design.
